UNITED STATES PATENT OFFICE.

SAMUEL J. BENSON, OF WASHINGTON, DISTRICT OF COLUMBIA.

PIPE-WRENCH.

SPECIFICATION forming part of Letters Patent No. 361,258, dated April 19, 1887.

Application filed January 27, 1887. Serial No. 225,640. (No model.)

To all whom it may concern:

Be it known that I, SAMUEL J. BENSON, of the city of Washington, in the District of Columbia, have invented certain Improvements 5 in Pipe-Wrenches, of which the following description, in connection with the accompanying drawings, is a specification.

My improvements relate to pipe-wrenches wherein the most desirable features of different classes are combined and concentrated with special modifications of construction and action, resulting in a wrench having decided practical advantages, and, when considered as herewith presented, differing materially from 15 any wrench known to me.

My object is to provide a wrench which can be quickly adjusted, having a positive grip, the strain and points of contact so divided that unnecessary crushing or flattening of pipes 20 may be avoided—a wrench in which the delicate actuating parts are inclosed and protected from external strains and blows, and having no unnecessary projections or bulging parts to interfere while operating in limited spaces, 25 and possessed of the essential qualities of cheapness and durability. I attain this object by the means and mechanism described in the following drawings, in which—

Figure 1 is a longitudinal elevation showing 30 the wrench as it appears when set on a pipe. Fig. 2 is a longitudinal section of Fig. 1. Fig. 3 is a vertical cross-section on the line *ab*, Fig. 2. Fig. 4 shows a modification of the abutment and pivotal bearings. Fig. 5 is a vertical cross-section on the line *a b*, Fig. 4.

Similar letters refer to corresponding parts in the different views.

The hooked lever A. A forms and includes the <-shaped fixed jaw B on this end of the 40 lever, and on the edge opposite to the jaw B is a serrated rack, C. Between C and *c* is the guide-bar and serrated rack, the remainder, forming the necessary continuation of the lever, terminating in any suitable hand-hold.

D is a movable sleeve sliding freely upon 45 the lever A. At S is shown the arrangement of the abutment and pivotal bearing of the vibrating serrated jaw E, and at F is the fulcrum upon which the movable sleeve vibrates 50 while being adjusted. This abutment and pivotal bearing may be cast solid into the sides *h* of the sleeve D.

E is a jaw having a serrated face. It is pivoted, as shown, and provided with an extension or thumb-piece, *e*. Under this is a spring, 55 R, which forces the jaw into contact with the pipe while working. This jaw is held in place and vibrates freely between the sides of the movable sleeve.

G is a serrated die, formed into or properly secured within the movable sleeve, and conforms to and interlocks with the corresponding rack, C, on the lever, which is located upon the lever on the end opposite to the handle, and on that edge of the lever opposite to and 65 farthest from the fixed jaw B.

At J is a spring to keep the serrated face on the lever at C and the serrations G in the movable sleeve in contact and to facilitate the adjustment of the wrench.

From F, on the angle of the dotted line to *d*, 70 a small open space is shown between the sleeve and lever, which allows room for a prying action resulting from the thrust of the jaw E, the strain and movement being in part transferred to and turning upon a fulcrum-point at F, thus pulling and prying the serrations C and G into firmer contact and increasing and assuring the certainty of the grip of the sleeve 75 upon the lever. The sleeve vibrates upon 80 this fulcrum-point F when the wrench is being adjusted to or removed from a pipe or other object.

Figs. 4 and 5 show the modifications above referred to. The difference results and grows 85 out of whether the serrated vibrating jaw E moves upon an internal or external pivotal bearing at S. The views and letters above given apply to corresponding parts. In using the internal bearing, cast solid in the sleeve, 90 the hub of the jaw E would be slotted to permit it to pass over and engage with the bearing at S, as shown.

The operation is as follows: The wrench is firmly grasped around the neck of the movable sleeve D, inclosing the extension *e* of the jaw E, which raises or throws outward the serrated end of the jaw E. The handle of the lever A being held in the other hand, a slight rocking movement in opposite directions releases 95 the interlocking serrations of the lever and sleeve, when the sleeve may be slid at will 100 upon the lever, in order to remove it from or to adjust it upon a pipe or other suitable ob-

ject. On releasing the sleeve the spring J snaps the notches or serrations of the sleeve and lever together. The spring R keeps the serrated face of the vibrating serrated jaw E in contact with the pipe as the lever is moved back and forth.

Having thus described my invention, what I claim as new, and desire to secure by Letters Patent, in a pipe-wrench, is—

10 The lever A, having the fixed hooked jaw B and provided with serrations C on the op-

posite edge and the same end of the lever, in combination with the movable sleeve D, having midway between its ends a fulcrum by which it vibrates upon the inner edge of the lever A, and carrying and inclosing the pivoted serrated jaw E, the springs R and J, and serrations G.

SAMUEL J. BENSON.
